[57] **CLAIM**

The ornamental design for a pair of extender jaws for a vise, substantially as shown and described.

DESCRIPTION

FIG. 1 is a perspective view of the pair of extender jaws for a vise showing my new design with the vise being shown in broken lines for illustrative purposes only; FIG. 2 is a top plan view thereof with the bottom view being substantially similar;

FIG. 3 is a side elevational view thereof with the opposite side being substantially similar;

FIG. 4 is an end elevational view thereof showing the outer surface of the jaw shown on the right side of the vise in FIG. 1;

The inner surface of the right jaw is substantially the same as the inner surface of the left jaw and the outer surface of the left jaw is substantially similar to the outer surface of the right jaw except for the placement of the stud bolts.
